UNITED STATES PATENT OFFICE.

GEORGE R. MEYERCORD, OF CHICAGO, ILLINOIS.

TRANSLUCENT PANEL FOR SIGNS AND ORNAMENTAL PURPOSES.

1,080,989.

Specification of Letters Patent.

Patented Dec. 9, 1913.

Application filed August 17, 1910. Serial No. 577,668.

To all whom it may concern:

Be it known that I, GEORGE R. MEYERCORD, a citizen of the United States, residing at Chicago, county of Cook, State of Illinois, have invented a certain new and useful Improvement in Translucent Panels for Signs and Ornamental Purposes, and declare the following to be a full, clear, and exact description of the same, such as will enable others skilled in the art to which it pertains to make and use the same, reference being had to the accompanying drawings, which form a part of this specification.

It is common to employ illuminating panels in signs and decorative work of various kinds. Heretofore such panels have been made of glass treated so as to be translucent but not quite transparent, thereby causing the glass to form a soft back ground for the subject of the sign or of the decoration. Because of the fragility of glass, it being easily cracked or broken, panels made thereof, in order to have any considerable strength, must be made thick and heavy. A heavy panel requires a strong heavy frame which adds to the expense and weight of the device containing the panel. Even where a maximum strength is obtained by increased weight, great care must be taken during the shipment, installation and use of devices having glass panels in order to prevent the panels from being damaged.

My invention has for its object to produce an attractive, strong and durable substitute for glass, particularly where used as a panel in the sign or decorative device intended to be illuminated.

A further object of my invention is to produce a translucent panel having thereon a colored translucent subject which will show in clear soft colors when the panel is illuminated.

The various features of novelty whereby my invention is characterized will be pointed out with particularity in the appended claims; but, for a full understanding of my invention and of its object and advantages, reference is to be had to the following detailed description taken in connection with the accompanying drawing, wherein:

Figure 1 is a front elevation of a sign embodying my invention; Fig. 2 is a sec-

tion taken at right angles to Fig. 1; Fig. 3 is a view on an enlarged scale of the face of the sign; and Fig. 4 is a transverse section on an enlarged scale through the panel illustrated in Fig. 3.

In carrying out my invention I make use of a perforated sheet, preferably in the form of a wire screen of fine mesh to form the body of the panel. On the screen I press a decalcomania film and also close the perforations or interstices with some adhesive translucent material, contrasting in color with the color of the film or of the subject formed by the film.

I have found that shellac may be used advantageously as the filler, since it adheres firmly to the body and, upon drying, presents a hard glossy surface. By using a wire or screen netting and clean shellac an imperforate panel may be used which has the appearance of perforate glass when viewed with the light shining through it, the shellac having sufficient opaqueness to render a lamp or other illuminating device in rear of the panel invisible from the front. The hardness and glossiness of the surface may be increased by mixing with the shellac a small quantity of powdered sodium silicate.

The panel may be produced in various ways. Thus the filler may be applied to the naked screen by means of a brush or by dipping the screen in a bath of shellac, varnish, or other suitable material. When the screen has become dry, the subject may be painted thereon in translucent materials or by pressing a translucent, colored decalcomania film upon the screen. When the filler is applied it leaves the surface of the panel uneven, the thickness of the panel as a whole being least at the center of the small squares bounded by the crossing wires and being thickest adjacent to the wires and particularly at the corners of the squares. When a decalcomania film is mounted on a surface of this kind, the pressure employed in mounting it causes it to conform closely to the supporting surface; the film being stretched over each square or interstice in the screen so as to make it contain numerous small cup-shaped depressions. Decalcomania films are resilient and elastic enough to permit this distortion when they are applied

but afterward, when they dry out and particularly when subjected to the heat of a lamp or other source of illumination, they become brittle and crack throughout the 5 stretched portions, unless some means is provided for preventing this. The cracking of the film destroys the beauty of the panel when illuminated and greatly decreases the value of the panel. In accordance with one 10 feature of my invention I provide means for preventing the cracking of the film under any ordinary conditions encountered in the service to which the panel is to be put. I accomplish this by covering the film with a 15 layer of shellac or varnish which serves the same purpose, as if the film were incorporated therewith, and therefore makes it necessary for the film to expand and contract with the elastic coating without permitting 20 cracks to appear.

While the panel may be made by first filling the interstices, then placing or mounting the subject thereon, and then applying the final coating, a simpler, cheaper and extremely efficient method is to press the decalcomania film directly upon the bare screen while the paper backing on which the film is mounted is in a wet state and then to dip the screen in the adhesive bath or 25 cover it on both sides with adhesive material in any suitable manner. In this way the varnish or shellac engages with both sides of the film at the same time that it reaches the wires of the screen, the inner surfaces of 30 the coatings on opposite sides taking the shape into which the film has been pressed and adhering closely to it. At the same time the interstices in the screen about the film are filled in the same manner as if the 35 screen were dipped or otherwise coated in its bare condition. I much prefer to make the panel by the last method, applying the coating by dipping the screen after the film has been applied. When the film is pressed 40 in place on the screen it is stretched into numerous cup-like sections each of which extends into one of the interstices of the screen. Because of failure of the adhesive material on the film to hold fast to the wires, or for 45 other reasons, it has been found that some of the cup-like sections will flatten out and assume their original shape when the pressure is removed from the film. This makes the decoration rough and uneven and detracts greatly from the beauty of the panel. 50 I have found, however, that by dipping the screen in varnish or shellac before the film has time to dry and set, and then allowing the excess of varnish or shellac to drip from 55 the panel, all of the flattened sections will again be drawn back into their cup-like form, thus preserving the uniformity of contour of the surface of the panel. This result seems to be caused by the viscosity of the

varnish or shellac which, entering between 65 the wires in rear of a flattened section of the film, sticks to the film and, as the excess of varnish or shellac flows off, a pull is exerted upon the flat film and it is again drawn into its cup-like shape. When the coating 70 hardens and sets the film is of course held rigid and can no longer become displaced.

Referring to the drawing, A represents a panel for a sign made in accordance with my invention and having painted thereon 75 the word "Cigars." In rear of the panel is an illuminating device, such as an electric light B. When the light is turned on a soft glow will emanate from the entire panel and the translucent letters will glow 80 brilliantly so as to produce an extremely attractive and pleasing effect.

In Figs. 3 and 4 I have illustrated a fragment of the panel on an enlarged scale. Thus a, a, and a', a', represent the two sets 85 of wires of an ordinary close meshed wire screen. a² is the filler and a³ the decalcomania film. The cross section of the panel will be the same as that shown in Fig. 4 regardless of which of the two methods of 90 manufacture is employed, the first coating of the screen merging itself into the second coating if the film is applied between two dippings and the thickness of the filling layer being also somewhat greater where 95 the filler is applied in two coats than where it is applied in one.

The surface of the panel may be washed in the same manner as glass while at the same time the panel is tougher and much 100 more durable. Furthermore, while I have shown in the drawing simply a plain panel, it is evident my improved material may be given any desired shape not only in its incomplete state and before the filler is applied, but even afterward, for my improved 105 material is extremely flexible and may be bent into many different forms without injury; in fact a sheet may be rolled up in the same manner as ordinary wire screening 110 without in any way affecting it.

While I have described in detail only a preferred embodiment of my invention and have illustrated it as applied to a simple sign, I do not desire to be limited to the specific devices disclosed since my invention may take many other forms as will be evident from the terms employed in the definitions thereof comprising the appended claims.

What I claim is:

1. A panel comprising a wire screen bearing directly thereon a decalcomania film having numerous small cup-like portions extending into the interstices of the screen, 125 and an adhesive coating covering the screen and filling the interstices behind said cup-like portions.

2. A panel comprising a wire screen bearing directly thereon a decalcomania film having numerous small cup-like portions extending into the interstices of the screen, and an adhesive coating covering the screen and filling the interstices and engaging with both sides of the film.

In testimony whereof, I sign this specification in the presence of two witnesses.

GEORGE R. MEYERCORD.
